CLAIM

The ornamental design for a removable skimmer basket handle, as shown and described.

DESCRIPTION

FIG. 1: is a left elevational view of a removable skimmer basket handle with base cap removed;

FIG. 2: is a front elevation view thereof;

FIG. 3: is a right elevation view thereof;

FIG. 4: is a perspective exploded view of a removable skimmer basket handle;

FIG. 5: is a bottom elevation view thereof; with base cap removed;

FIG. 6: is a top elevation view thereof;

FIG. 7: is a back view thereof;

FIG. 8: is a left elevational view of removable skimmer basket handle with the top handle portion removed;

FIG. 9: is a top elevation view thereof;

FIG. 10: is a right elevation view thereof;

FIG. 11: is a perspective elevation view thereof;

FIG. 12: is a bottom elevation view thereof;

FIG. 13: is a front elevation view thereof;

FIG. 14: is a back view thereof; and,

FIG. 15: is a perspective view of the handle and base cap together in a skimmer basket showing in an environment. The broken line shown in FIG. 5 and FIG. 12 show portions of the article not claimed.

The broken line shown in FIG. 15 show environment and form no part of claim design.

1 Claim, 15 Drawing Sheets
